UNITED STATES PATENT OFFICE.

EDWARD A. DUNN, OF HAVERHILL, MASSACHUSETTS, ASSIGNOR TO UNITED SHOE MACHINERY CORPORATION, OF PATERSON, NEW JERSEY, A CORPORATION OF NEW JERSEY.

FINISHING MACHINE.

Application filed June 8, 1925. Serial No. 35,732.

This invention relates to finishing machines and is herein illustrated as embodied in a machine of the type disclosed in United States Letters Patent No. 1,078,050, granted 5 November 11, 1913, on application of Elmer Lane, for buffing shoe blanks or shoe parts, such as toe-stiffeners, counter-stiffeners and the like.

In the manufacture of boots and shoes, 10 certain parts, of which toe and counter-stiffeners are typical, are cut from sheet material and the margins of the blanks are skived to a feather edge. It is then customary to buff the beveled surfaces of a skived blank and 15 the adjacent central portion of the blank to provide a smooth and uniform surface with which the beveled edges will merge. This operation is commonly performed by the use of machines of the type above referred to. 20 In the use of such machines, the counter-stiffener or other piece of work is presented to a resilient abrasive covered buffing roll by a feed roll usually provided with a yieldable facing, and a presser plate extending 25 close to the bite of the feed roll and the buffing roll operates to depress the work piece against the yieldable facing of the feed roll. This action tends to depress the central thicker portion of the counter or other work 30 piece more than the thin skived edges to prevent removing an undesirable amount of material from the thicker central portion and presents the work piece to the buffing roll in such a manner that material is removed principally from the portions of the 35 work piece adjacent to the skived margins in order that the skived margins may be blended with the central surface.

An object of the present invention is to 40 provide an improved machine of the general type above referred to, by which the buffing of counter-stiffeners and similar articles may be still further facilitated, to the end that the quality of the buffing may be improved and at the same time increased production may be attained.

To this end, in accordance with one feature of the invention, the untensioned resilient supporting surface of the buffing roll of the 45 illustrated machine is provided with a circumferential depression or groove which is normally bridged by the abrasive material by which the buffing is performed. By properly dimensioning the above-mentioned

depression with respect to the particular 55 pieces of work upon which the machine is to be utilized, adequate treatment of all the surfaces, including the beveled periphery and the intermediate central portion is insured, without unduly thinning the central 60 portion, because the abrasive covering of the roll is depressed into the groove by the thicker central portions of the pieces of work thereby preventing the application of undue 65 pressure by the buffing roll upon those portions even when they are forced out of the resilient covering in which they have been embedded and into the space between the end of the presser plate and the bite of the rolls, thus reducing to a minimum the 70 amount of material removed from the thicker central portions. At the same time the arrangement provides full pressure and action 75 of the abrasive roll upon the skived parts of the blanks with the assurance that the various surfaces upon the faces of the blanks to be treated will merge gradually and uniformly one into the other without any perceptible break therebetween and that the peripheries will be reduced to a feather edge. 80

It has been common in machines of the type under discussion to utilize a buffing roll the length of which is several times the width of a single piece of work, with the result that it has been usual for the operator 85 to feed successive pieces of work along substantially parallel paths and without waiting for the buffing of a single piece of work to be completed to insert a succeeding piece of work between the rolls. Considering the 90 present invention in another aspect, such presentation of work pieces is facilitated by provision in the illustrated machine of a plurality of circumferential grooves arranged side by side along the buffing roll, thereby 95 aiding the operator in presenting successive pieces of work in parallel paths and making it practicable to speed up the production of the machine.

These and other features of the invention 100 are described in the following specification and illustrated in the accompanying drawing, in which:

Fig. 1 is a perspective view of the upper portion of a finishing machine with parts 105 broken away;

Fig. 2 is a view of the buffing roll and the feed roll with parts broken away and in

section to show the position of a piece of work when passing between the rolls;

Fig. 3 is a transverse section through said rolls and the presser plate; and

5 Fig. 4 is a perspective view of a portion of a counter after it has been buffed by the machine.

As above stated, the illustrated buffing machine is a machine of the general type 10 closed in United States Letters Patent No. 1,078,050, to which reference may be had for a more complete disclosure of parts not fully described herein. The machine shown in the drawings comprises a rapidly rotating buffing 15 roll 14 and a feed roll 18 placed adjacent thereto which is rotated oppositely so that the active part of its periphery moves with the adjacent periphery of the buffing roll but at a much slower speed. A presser 36 is provided 20 for pressing a counter-stiffener or other piece of work against the feed roll 18 which causes the work to be carried along gradually while it is being acted upon by the rapidly rotating buffing roll 14.

25 In the illustrated machine, of which only the head 10 is shown, the buffing roll 14 is on a belt-driven shaft 12. The buffing roll is rotated in a counterclockwise direction, when viewed from the right-hand end (Fig. 1), 30 usually at from three thousand to four thousand revolutions per minute. Another belt-driven shaft 16 provides a support for the feed roll 18 which is covered with a resilient facing, illustrated as of rubber, and this feed 35 roll is rotated in a clockwise direction, when viewed from the right-hand end, at a much slower speed. The arrangement is such that the plane including the axes of the two shafts is inclined, as illustrated in Fig. 3, for the 40 convenience of the operator, and a throat plate 20 extending across the front of the machine is slidably mounted upon an inclined surface 22 which is parallel to the plane of said shafts. Adjusting screws 24 and 26 and 45 clamping screws 28 are provided in order that the position of this throat plate 20 may be carefully determined and fixed. The lower intermediate portion 30 of the throat plate is curved to form a cover for the feed roll while 50 the upper, transverse portion 32 is spaced from the portion 30 to provide an opening for the insertion of pieces of work and has a lower surface 34 positioned at an abrupt angle to the inclined surface 22. A rigid presser plate 55 36 resting against the surface 34 is adjustably secured in position thereon by means of screws 38 passing through slots in said presser plate. The forward edge of the presser plate is beveled and is brought to a position closely 60 adjacent to the bite of the two rolls and is then adjusted by means of screws 24 and 26 so that pieces of work inserted through the opening of the throat plate are brought into contact with the feed roll 18 with the result 65 that the pieces of work are pressed into the

surface of the feed roll sufficiently to be carried forward at the speed of the feed roll. A hood 40, shown in Fig. 1 in raised position, is arranged to cover the upper half of the buffing roll and, in conjunction with other parts of the machine not shown, to form a suction conduit for drawing away the dust made during the abrading operation. An inclined, perforated plate 42 positioned below the rolls guides the pieces of work back into 75 position for easy removal by the operator.

The illustrated buffing roll 14 is a split cylindrical roll of the type disclosed in United States Letters Patent No. 868,021, granted October 15, 1907, upon the application of J. R. Scott. The abrasive covering material 54, after having been wrapped around the opened roll 14 with the meeting edges of the covering material engaging the prongs 15, is drawn taut as the roll is closed and the parts of the 80 roll are held together by end collars 44 (Fig. 2) having cam slots 45 to coact with the pins 47 upon the roll to draw them together and tension the abrasive cover circumferentially. As in the patented construction referred to 85 above, the prongs 15 of the present application are likewise disposed between the ends of the roll 14 and constitute means for gripping the meeting edges of the abrasive sheet 54 to clamp it tightly around the roll 14 when the latter is closed, the prongs 15 thus being arranged to tension the sheet 54 circumferentially. The buffing roll 14 is dimensioned so that it is suitable particularly for use in buffing leather counters to be used in the construction of boots and shoes, such as that shown at 90 46 in Fig. 4. The roll 14 has an untensioned yieldable covering, illustrated as of soft rubber, in which, between the ends of the roll 14, is formed a plurality of shallow circumferential recesses or grooves 50 of curved cross-section with the edge portions of the grooves merging gradually into intermediate portions 52 between said grooves which are left at the 95 normal diameter of the roll. When an abrasive cover 54 such as sandpaper is wrapped around this roll, it is supported upon the intermediate and end portions 52 and bridges the grooves 50.

100 Such an abrasive cover is sufficiently resili- 115 ent so that upon the insertion of a piece of work such as a counter 46 between the rolls at a position coinciding with one of the grooves 50 in the buffing roll the pressure of the central portion of the piece of work 46 120 causes the depression of the portion of the cover 54 which overlies the groove 50 into the groove, tending to wrap the cover around the curve of the work, thus increasing the action of the buffing roll upon the beveled edges 125 of the counter and reducing its action upon the central portion. The portions of the abrasive cover 54 which contact with the beveled edges of the counter are much better supported by the rubber surface of the buffing 130

roll because they overlie portions 52 of said roll adjacent to the edges of a groove 50 and hence come into contact with the surface of the roll with less deflection than those portions 5 of the cover which overlie the central portion of the groove. Accordingly, the action of the buffing roll upon the edges of the piece of work is, as desired, substantially increased and brings these parts of the work to 10 a feather edge. The above described buffing roll, by reason of its grooved construction, can accommodate the thicker central portions 15 of a work piece without pressing too heavily upon those portions, even if those portions are not embedded, or are only partially embedded, in the resilient cover of a feed roll. A work piece which has been embedded in the cover of a feed roll by a presser plate may, especially if lacking in stiffness, be forced more 20 or less out of the cover in which it has been embedded after it leaves the presser plate, since the latter cannot extend all the way up to the bite of the rolls. In such cases, and especially in the treatment of thin flexible material, 25 the above-described grooved buffing roll presents a marked advantage over the ordinary cylindrical roll. By the provision of a plurality of grooves in the buffing roll the operator is helped to feed successive pieces of 30 work along parallel paths without waiting for the completion of the operation upon a single piece of work and thereby greatly to increase the production of the machine. The cross section of the grooves in the buffing roll 35 approaches closely that of the counters so that the desired support is afforded to the abrasive cover at all points but, by properly dimensioning the grooves 50, the machine may be used for other similar pieces of work, as 40 above mentioned.

It will be noted that the feed roll 18 acts directly through the thickness of the counter 46 for pressing the latter against the roll 14 to deflect the abrasive sheet 54 into the groove 50 45 so as to tend to curve the sheet around the counter.

Having described the invention, what I claim as new and desire to secure by Letters Patent of the United States is:

50 1. A finishing roll of substantially cylindrical form provided with a yieldable supporting peripheral surface having a circumferential groove between the ends of the roll, a sheet of abrasive material wrapped around said roll and bridging said groove, and means disposed between the ends of the roll for gripping the meeting edges of said sheet of material to clamp it tightly around the roll arranged to tension the sheet circumferentially.

2. In a finishing machine, a cylindrical buffing roll provided with an untensioned yieldable covering, said covering being provided with a circumferential recess, a sheet 55 of abrasive material wrapped around said roll

and normally bridging the recess of said yieldable covering, and means adapted to act directly through the thickness of a piece of the work for pressing said piece of the work against said roll to deflect said sheet of abrasive material into the groove so as to tend to curve said sheet around the work. 70

3. A buffing roll of substantially cylindrical form provided with a resilient supporting surface having a circumferential groove between the ends of the roll, a sheet of abrasive material wrapped around said roll and bridging said groove, and means disposed between the ends of the roll for gripping said sheet of material to clamp it tightly around the roll in 75 contact with the ungrooved portions thereof.

4. In a finishing machine, a cylindrical treating tool the length of which is several times the width of a single piece of work to be treated and having a plurality of parallel 85 grooves disposed circumferentially of the tool between its ends, and a feed roll for presenting pieces of work to the treating tool in positions overlying said grooves so that a plurality of pieces of work may be treated 90 at the same time.

5. In a finishing machine, a substantially cylindrical abrading tool the length of which is several times the width of a single piece 95 of work to be treated, said tool having a yielding surface provided with a plurality of parallel shallow grooves of curved cross-section disposed circumferentially of the tool between its ends, and a cylindrical feed roll positioned closely adjacent to said abrading 100 tool for presenting pieces of work to the treating tool in positions overlying said grooves so that a plurality of pieces of work may be treated at the same time.

6. A buffing roll of substantially cylindrical form provided with a resilient supporting surface, said surface having a circumferential groove of curved cross-section with the edge portions merging gradually into the ungrooved adjacent portions of the roll, and means for clamping a sheet of abrasive material around said roll to bridge said circumferential groove constructed and arranged to grip the meeting edges of the sheet of material to hold it tightly in position without tensioning the surface of the roll. 110

7. In a finishing machine, a buffing roll of substantially cylindrical form having a resilient surface, said roll being provided with a circumferential groove between the ends of the roll, a sheet of abrasive material wrapped around said roll and normally bridging the groove therein, and a feed roll having its axis substantially parallel to the axis of the buffing roll arranged with its periphery closely adjacent to the periphery of the ungrooved portion of the buffing roll to support a piece 120 of work and press it into said groove.

8. In a finishing machine, a cylindrical buffing roll split longitudinally, said roll be- 125

ing provided with a yielding surface having a circumferential groove between the ends of the roll, a sheet of abrasive material wrapped around the roll and normally bridging the circumferential groove and having its ends inserted between the split portions of the roll, means for holding the portions of the roll together to clamp the abrasive covering in position, and a feed roll for presenting a piece of work to said buffering roll arranged with its surface closely adjacent to said abrasive covering.

9. In a finishing machine, a cylindrical buffering roll having a yieldable supporting surface provided with a plurality of circumferential grooves, a sheet of abrasive material wrapped around said roll bridging said grooves, means for clamping said sheet of material in position upon the roll, and a feed roll arranged with its peripheral surface adjacent to the abrasive covering upon said buffering roll, said feed roll extending longitudinally to cover more than one of the grooves in the buffering roll so that a plurality of pieces of work may be treated at the same time.

10. In a finishing machine, a cylindrical buffering roll having a yieldable supporting surface provided with a circumferential groove between the ends of the roll, a sheet of abra-

sive material wrapped around said cylindrical roll and normally bridging the circumferential groove, means for clamping said sheet of material in position upon the roll, a feed roll disposed adjacent to the abrasive covering upon the buffering roll arranged to press a piece of work into the groove of the buffering roll, and a presser plate having its leading edge disposed closely adjacent to the bite of the buffering roll and the feed roll and arranged to press a piece of work against the feed roll sufficiently to ensure the feeding of the piece of work to the buffering roll.

11. In a finishing machine, a cylindrical buffering roll having a yieldable surface provided with a plurality of parallel shallow grooves disposed circumferentially of the roll between its ends, a sheet of abrasive material covering said roll and normally bridging said grooves, means for clamping said sheet of material upon the roll, a feed roll arranged in parallel relation to the buffering roll for presenting pieces of work to the abrasive covering in positions overlying said grooves, and means for holding pieces of work in feeding contact with said feed roll.

In testimony whereof I have signed my name to this specification.

EDWARD A. DUNN.
